SKYLIGHT

Dennis E. Helma, 8117 Ozanam, Niles, Ill. 60648

Filed Sept. 29, 1967, Ser. No. 8,795

Term of patent 14 years

U.S. Cl. D23—153
Int. Cl. D23—04

Fig. 2.

Fig. 1.

FIGURE 1 is a perspective view, taken from above, of a skylight showing my new design.

FIGURE 2 is a side elevational view of the skylight of FIGURE 1, the other three sides being mirror images thereof.

FIGURE 3 is a perspective view, taken from below, of the skylight of FIGURE 1, showing a first embodiment of my new design, wherein the underside of the skylight is provided with a smooth surface which is recessed as shown.

FIGURE 4 is a fragmentary sectional view of the embodiment of FIGURE 3 taken along line 4-4 of FIGURE 3.

FIGURE 5 is a perspective view, taken from below, of the skylight of FIGURE 1, showing a second embodiment of my new design, wherein the underside of the skylight has a generally open appearance as shown.

FIGURE 6 is a fragmentary sectional view of the embodiment of FIGURE 3 taken along line 6-6 of FIGURE 3.

The design is characterized by the outwardly projecting rim at the top of the skylight, by the continuous lip

on the underside of said rim which depends in spaced parallel relation to all four sides of the skylight and lies inwardly of the outer edges of the outwardly projecting rim, and by the intersecting channels which also lie on the underside of the outwardly projecting rim between the outer edges of the outwardly projecting rim and the downwardly projecting lip.

I claim:

The ornamental design for a skylight, substantially as shown and described.
